FLEXIBLE TEST PROB

Vincent E. Wattley, Bronx, N. Y.

Application December 18, 1944, Serial No. 568,694

1 Claim. (Cl. 173—273)

1

This invention relates to improvements in instruments particularly well adapted for use in repairing electrical equipment wherein it is necessary to bridge contacts, lead wires or other electrical terminations.

The primary object of this invention is the provision of a tool for use in the radio and electronic field by means of which a technician may make temporary electrical connection between radio or electronic equipment and indicating or test instruments without the liability of shorting and with complete safety to the technician.

Other objects and advantages of the invention will appear in the following detailed description.

In the accompanying drawings, forming a part of this specification, and wherein similar reference characters designate corresponding parts throughout the several views:

Figure 1 is a perspective view of the improved tool.

Figure 2 is a perspective view of one type of probing end for the tool.

Figure 3 is a perspective dotted line view showing a clamping position of the jaws of the tool end shown in Figure 2.

Figure 4 is a perspective view showing another type of tool end adapted to be used with the improved device.

Figure 5 is a longitudinal cross sectional view taken thru the tool end of Figure 4.

Figure 6 is a fragmentary sectional view showing the manner of attachment of the hand grasping portion to the metallic shaft of the tool.

Figure 7 is a longitudinal cross sectional view taken thru the improved tool of Figure 1.

Figure 8 is a longitudinal cross sectional view thru the tool showing the same assembled with parts which enable the tool to reach otherwise inaccessible areas.

Figure 9 is a fragmentary longitudinal sectional view showing the operating end of the tool of Figure 7 partly closed.

Figures 10 and 11 are cross sectional views taken substantially on their respective lines in Figure 7 of the drawings.

In the drawings, wherein for the purpose of illustration is shown a preferred embodiment of the improved tool, the letter A may generally designate the tool. It may appropriately be referred to as a probing tool or prodder and its distinguishing characteristic is that the tool is so insulated as to permit its safe and efficient use in establishing temporary connections between testing equipment and radio and electronic instruments, etc.

2

In the preferred instance, the tool is provided with a rigid assemblage where the terminals to be connected are accessible within the range of the tool; the tool including flexible means by which it is adaptable for reaching otherwise inaccessible located terminals.

In the tool as illustrated in Figures 1 and 7, the same comprises a rigid metallic casing assemblage including an upper part 15 and a lower part 16 detachably connected at 17 so as to define a passageway 18 for slidably receiving a reciprocating plunger shaft 20. The latter fits snugly in the passageway 18 of the part 16 without lateral play. The metallic casing portion 15 has its passageway enlarged at 18a and at its end defines an internal seat 25 facing the passageway. At the hand engaging end of the tool the casing portion 15 is internally screw threaded to detachably receive therein a reduced externally screw threaded end of an insulation cap 30. In lieu of this arrangement, the cap may be internally screw threaded to receive external screw threads of the casing, if so desired.

The plunger or operating rod 20 slidably reciprocates thru a passageway 31 in the cap 30 and within the passageway 18a the rod is provided with an annular flange 33. The spiral spring 34, under compression, engages this flange at one end and the seat 25 at the other end. It is under normal compression sufficient to properly position the plunger, as will hereinafter be described. The end of the plunger 20, where it extends thru the cap 30, is reduced, as shown at 40 in Figure 6 of the drawings and thereon receives an insulation sleeve 41. The extreme end of the portion 40 receives an insulation hand bar or handle 42. It is internally screw threaded at 43 from an outer end thereof, to receive a set screw 44 by means of which the handle may be detachably connected to the end of the portion 40 of the plunger. The sleeve 41 extends from the flange 33 to the handle 42, so that no part of the metal portion of the plunger is exposed.

The metallic casing portion 15 is externally covered with an insulation sleeve 50, shown in Figure 7 of the drawings, which at the hand grasping end is provided with lateral extensions 51 defining a handle bar of about the same nature as the bar 44 and complementary thereto. The sleeve 50 entirely covers the casing portion 15 from end to end. In similar manner, the casing portion 16 at the lower end of the tool is externally provided with an insulation sleeve 60 which covers the same from its outer operating end up to the point where it is screw threaded for connection with the casing part 15. These insula-

tion sleeves 50 and 60 are complementary and when the casing parts 15 and 16 are connected, there is no exposed metal at the joint. The tool, as thus provided, may taper with a decreasing diameter from handle to the tool operating end.

The outer end of the casing portion 16 is flared at walls 65 and 66, and the opposite side walls 67 are parallel. This defines a rectangular-shaped opening 70, as shown in Figure 1 of the drawings. The insulation of the sleeve 60 extends over these walls at the end of the casing 16 so that the outer end of this casing 16 is not exposed. There is an overlap of the insulation, as shown in Figure 9.

I prefer to provide several operating connectors for use with the plunger 20. To that end the outer end of the plunger 20 is internally screw threaded at 80. One type of tool is shown in detail in Figures 1, 2, 3, 7, 8 and 9 of the drawings and consists of a shank or body portion 81 having a screw threaded end 82 for detachable connection in the socket 80. The body portion 81 is of about the same diameter as the plunger 20 and slides within the passageway of the casing 16, as shown in Figure 9. The outer end of body 81 is provided with divergently disposed spring jaws 82 and 83 which inherently assume the open position shown in Figures 2 and 8 of the drawings. The material of the connector is, of course, such as to establish an electrical connection; preferably being metal. The jaws 82 and 83 have terminal gripping ends 85 which are exposed; the said jaws being otherwise covered at their outer ends with insulation sleeves 87 which extend from the tip ends of these jaws to a point where the same will enter the flaring mouth of the tool casing when the jaws are retracted, as shown in Figure 7 of the drawings.

In the position of the tool part shown in Figure 7, it is seen that the spring 34 retracts the tool so that the jaws 82 and 83 will be pressed together. The length of the passageway 18^a and the spring is such that when the plunger is forced forwardly it can extend the tool end out of the housing or casing of the tool to the point of connection of the screw threaded shank 82 in the socket end 80 of the plunger 20, so that the tool end may, with facility, be detached, and another connector placed upon the plunger.

The cam action of the jaws upon the flaring wall of the end of the casing part 16 can be seen in Figure 9 of the drawings where the plunger is being retracted into the casing and the jaws are being forced to a closing position.

Another type of probing tool connector is shown at 90 in Figure 4 of the drawings. This consists of a body portion 91 having a screw threaded shank 92 adapted to fit in the socket end of the plunger 20. At its outer end the body 91 has a pyramidal-shaped portion 94 adapted to fit snugly in the flared mouth of the casing 16. The tool part includes a reduced conductor end 94 having an enlarged connector point 95. The shank 94 is covered by means of an insulation sleeve 96 and the exposed end of the pyramidal-shaped portion 94 is also covered with insulation, as shown at 97.

Use of the tool connector of Figures 4 and 5 will be well understood by those skilled in the art of radio and electronic repair or testing equipment. In position in the casing portion 16, the pyramidal-shaped portion 94 will fit snugly in the flared mouth of the casing 16 and no part thereof will project. The insulation wall 97 prevents exposure of any metallic part of the tool connector 90 except the pointed conductor end 95.

The tool assembly above described is adapted to be used where the operator can properly insert the tool into the equipment to be tested in a straight line. There are, of course, inaccessible areas and locations where a tool of this sort will have to be used. For this purpose I provide a plunger 20^a having all of the characteristics of the plunger 20 above described, so far as spring mounting and insulation are concerned, except that at the forward end the plunger is provided with a flexible body portion 20^b, in the nature of a Bowden wire which at its forward end is provided with a socket providing portion 20^c to which the tool connector parts above described may be attached. In lieu of the metallic casing portion 16, which is of rigid nature, I provide a flexible metallic tube 16^a which has an end 16^b provided with screw threads for detachable connection in the internal screw threaded socket of the part 15.

The outer end of the flexible tube 16^a is provided with a portion 16^c of the same nature as the flared end of the rigid tool casing 16, above described. A flexible insulation sleeve 60^a covers the metallic portion of the sleeve 16^a and the associated parts 16^b and 16^c. Except for these variations, the parts of the tool assemblage both in construction and operation, are identical with respect to those of the rigid type tool above described.

It is possible to operate this tool under such conditions that electrical connections between terminals, lead wires and contacts may be established with great facility. The operator need only use one hand since the handle bar 34 may rest against the thumb or in the palm of the hand and adjacent fingers used with the bar extensions 55 to perform the reciprocatory function of the plunger.

The insulation parts of the instrument may be of rubber, synthetic resin or any thermoplastic material. It will be noted that all metallic parts of the instrument are covered when the instrument is in repose, as shown in Figure 1, except the contact tips at the ends of the jaws, and that is also true of the flexible type of tool shown in Figure 8.

Various changes in the shape, size and arrangement of parts may be made to the form of invention herein shown and described, without departing from the spirit of the invention or the scope of the following claim.

I claim:

In a tool for use in connection with electrical appliances the combination of an elongated casing insulated from end to end and having laterally extending opposed handles at one end thereof and an open outwardly flared mouth at the opposite end, said casing having a passageway therethru and a flared entrance in said mouth, a reciprocatory plunger in said passageway having an end extending from that end of the casing which is provided with handles, said plunger at its end adjacent the handles of the casing being provided with insulation handles spaced from and beyond the handles of the casing, spring means normally forcing the handles of the casing and plunger relatively apart and retracting the plunger within the casing, and a pair of inherently opening spring gripping jaws connected upon the end of the plunger opposite the handles, said plunger and jaws being so constructed and arranged with respect to the casing that when the plunger is urged by the spring means to the limit of its retraction in the casing said jaws will engage in the flared mouth in a contracted clamping relation, said casing and

plunger each including a rigid portion adjacent to the handle end of the tool and a long flexible portion connected to the rigid portion at the jaw end of the tool, the flexible portion of the plunger being disposed within and operating within the flexible portion of the casing to assume a flexible length of the assembled device.

VINCENT E. WATTLEY.
